(57) **CLAIM**

The ornamental design for a shoe as shown and described.

DESCRIPTION

FIG. 1 is a front perspective view of a shoe showing our new design;
FIG. 2 is a side view thereof;

FIG. 3 is a front perspective view of the shoe of FIGS. 1-2 with shading added to more clearly demarcate between the claimed regions and the regions which form no part of the claimed design; and,
FIG. 4 is a side view thereof.

The interstices between the grid elements form no part of the claimed design. The broken lines immediately adjacent to the center and the bottom of the grid define the bounds of the claimed design and form no part thereof. The broken lines immediately adjacent to the inner edges of the two raised elements overlaying the grid define inner bounds of the claimed design and form no part thereof. The broken lines depicting the remainder of the shoe form no part of the claimed design.
